(57) **CLAIM**

What is claimed is the ornamental design for a light fixture segment, as shown and described.

DESCRIPTION

FIG. 1 is a perspective view as viewed from above of the light fixture segment of our design;

FIG. 2 is a perspective view as viewed from below thereof;
FIG. 3 is a front elevational view thereof, where the rear, right and left side elevational views are identical images of this view and, therefore, have been omitted;

FIG. 4 is a top plan view thereof; and,
FIG. 5 is a bottom plan view thereof.

The broken lines in the drawings are directed to environment and are for illustrative purposes and form no part of the claimed design.

The light fixture segment is shown with symbolic break lines along its length. The appearance of any portion of the article between the break lines forms no part of the claimed design. A separation and a bracket are used to indicate that, for ease of illustration, the precise length, width, and height dimensions and proportions of the article are not claimed.

The light fixture segment is not limited to the scale shown herein.

1 Claim, 5 Drawing Sheets
